UNITED STATES PATENT OFFICE.

ALBERT G. TUBBS AND LISLE W. SWEET, OF GHENT, NEW YORK.

GARMENT.

1,247,469.

Specification of Letters Patent. Patented Nov. 20, 1917.

Application filed May 16, 1917. Serial No. 168,912.

To all whom it may concern:

Be it known that we, ALBERT G. TUBBS, a citizen of the United States, and LISLE W. SWEET, a citizen of the United States, both residents of Ghent, in the county of Columbia and State of New York, have invented a new and Improved Garment, of which the following is a full, clear, and exact description.

10 The invention relates to union suits and its object is to provide a new and improved garment of the jacket and trouser type in which an upper piece of wearing apparel such as a jacket or a bib can be interchangeably attached to and worn with the trousers.

15 In order to accomplish the desired result, use is made of trousers provided at the upper front portion with spaced lacing openings, an upper piece of wearing apparel such 20 as a jacket or a bib provided at its lower portion with lacing openings, and a lacing interlaced with the said sets of lacing openings to detachably fasten the said trousers and the said upper piece of wearing apparel 25 together.

30 A practical embodiment of the invention is represented in the accompanying drawings forming a part of this specification, in which similar characters of reference indicate corresponding parts in all the views.

35 Figure 1 is a front perspective view of the garment as applied;

Fig. 2 is an enlarged cross section of the garment on the line 2—2 of Fig. 1;

40 Fig. 3 is an enlarged front elevation of the garment with a portion of the jacket broken out to show the lacing connection between the trousers and the jacket;

Fig. 4 is an enlarged sectional plan view 45 of the garment on the line 4—4 of Fig. 3;

Fig. 5 is a front elevation of the lower portion of the jacket in opened-up position;

Fig. 6 is a front perspective view of the upper portion of the trousers partly opened 50 up; and

Fig. 7 is an inner face view of the bib.

The trousers 10 are provided at the upper front portion with an opening 11 having fastening devices 12 such as buttons and 55 buttonholes for closing the opening 11. The

sides of the upper portion of the trousers are provided with openings 13 adapted to be closed by fastening devices 14 such as buttons and buttonholes, it being understood 55 that the openings 13 provide the rear upper portion of the trousers 10 with a sanitary drop flap 15, as plainly indicated in Figs. 2

and 6. The drop flap 15 is provided with an upward extension 16 from which extend diverging shoulder straps 17 provided at their ends with attaching members 18 such as loops. The divided upper front portions of the trousers 10 are provided with waistbands 20, 21 having spaced lacing openings 22 23 preferably in the form of vertical 65 slits, as plainly indicated in Fig. 6.

A jacket 25, such as shown in Figs. 1, 2, 3, 4 and 5, may be detachably connected with the trousers 10, or a bib 26 (see Fig. 7) may be connected with the trousers instead of the jacket. The jacket 25 is open along the median front line, as indicated at 30, and the parts fastened together by suitable fastening devices 31 such as buttons and buttonholes. The lower front portions 32 and 33 of the jacket 25 are provided on the inner faces with flaps 34, 35 fastened in place along their upper edges by stitches 36, 37. The flaps 34 and 35 are provided with spaced lacing openings 38, 39 adapted to register 80 with the lacing openings 22 and 23 on the waistbands 20, 21 of the trousers. Bands or lacings 40, 41 are secured to the lower portions 32 and 33 adjacent the outer ends of the flaps 34, 35, as plainly indicated in Fig. 5, and the said lacings 40 and 41 are adapted to be interlaced with the registering lacing openings 38, 22 and 39, 23 to fasten the jacket and trousers together. The free ends of the lacings 40 and 41 are provided with 90 hooks 42, 43 adapted to engage loops 44, 45 (see Fig. 4) attached to the flaps 34 and 35 at the outer sides thereof. It is understood that the hooks 42 and 43 are engaged with the loops 44 and 45 after the lacings 40 and 41 have been interlaced with the registering lacing openings 38, 22 and 39, 23. By 95 the arrangement described the lacings 40 and 41 are not liable to become accidentally disconnected and hence the jacket and trousers are securely fastened together at their front portions. By arranging the flaps 34, 35 on the inner faces of the jacket portions 32 and 33 the lacings are not visible and a snug fit is had around the waist of the 100 wearer, as will be readily understood by reference to Fig. 1.

The front of the jacket 25 is provided on opposite sides of the front opening 30 near the shoulder portions with attaching members 50 and 51 in the form of buttons and adapted to be engaged by the attaching members 18 on the ends of the shoulder straps 17, as previously mentioned. The attaching

members 50 and 51 are concealed by side-wise extending reinforcing bands 52, 53 attached to the jacket at the outside thereof and extending from the median front line 5 30 to the sleeve seams, as plainly indicated in Fig. 1. By the arrangement described the attaching members 18, 50, 51 are completely concealed by the straps 52 and 53 when the garment is worn. It will be noticed that by the arrangement described the trousers 10 are supported from the front of the jacket by the lacings 40 and 41 interlaced with the lacing openings 38, 22 and 39, 23, and the rear of the trousers is supported from the shoulders of the wearer by the usual shoulder straps 17 connected with the front of the jacket by the attaching members 18, 50, 51. By unhooking the hooks 42, 43 from the loops 44, 45 and disconnecting the attaching members 18 from the attaching members 50 the jacket can be readily disconnected from the trousers on pulling the lacings 40, 41 out of the lacing openings and swinging the shoulder straps 25 17 backward.

Instead of the jacket, the bib 26 may be used in conjunction with the trousers 10 and for this purpose the bib 26 is provided on the inner face of its lower portion with a flap 60 having spaced lacing openings 61 adapted to register with the lacing openings 22 and 23 on the trousers. A lacing 62 is attached at one end to one side of the lower portion of the bib 26 and the free 35 end of the lacing 62 is provided with a hook 63 adapted to be hooked onto a loop 64 attached to the inner face of the flap 60 after the lacing 62 has been interlaced with the registering lacing openings 61, 22, 23. 40 By the arrangement described the lower portion of the bib 26 can be detachably connected with the upper front portion of the trousers 10. The upper portion of the bib 26 is provided with spaced attaching members 65, 66 such as buttons adapted to be engaged by the attaching members 18 on the forward ends of the shoulder straps 17 to hold the bib 26 in position on the front of the wearer and to hold the shoulder 45 straps in proper position over the shoulders of the wearer.

Although we have shown and described a jacket 25 or a bib 26 to be connected with the trousers as described it is evident that 50 we do not limit ourselves to any particular form of an upper piece of wearing apparel such as a jacket or a bib.

The trousers are provided with the usual pockets 70.

60 Having thus described our invention, we claim as new and desire to secure by Letters Patent:—

1. A garment, comprising trousers adapt-

ed to be opened and closed at the upper portion of the front median line, the said 65 upper portion being provided with spaced lacing openings extending from the front median line to the sides, a jacket adapted to be opened and closed at the front median line and provided at the lower front portion with spaced lacing openings, lacings interlaced with the said sets of lacing openings to detachably fasten the front upper portion of the trousers to the front lower portion of the jacket, each of the said lacings having one end attached to the jacket and having the other end provided with a hook, and a loop attached to the jacket near each side for engagement by the hook of the corresponding lacing. 80

2. A garment, comprising trousers adapted to be opened and closed at the upper portion of the front median line, the said upper portion being provided with spaced lacing openings extending from the front 85 median line to the sides, a jacket adapted to be opened and closed at the front median line and provided at the lower front portion with concealed flaps having spaced lacing openings, lacings interlaced with the 90 said sets of lacing openings to detachably fasten the front upper portion of the trousers to the front lower portion of the jacket, each of the said lacings having one end attached to the jacket and having the other 95 end provided with a hook, and a loop attached to the jacket near each side for engagement by the hook of the corresponding lacing.

3. A garment, comprising trousers adapt- 100 ed to be opened and closed at the upper portion of the front median line, the said upper portion being provided with spaced lacing openings extending from the front median line to the sides, the trousers having 105 a sanitary back flap provided with shoulder straps, a jacket adapted to be opened and closed at the front median line and provided at the lower portion with concealed flaps extending from the front median line 110 to the sides, the flaps having spaced lacing openings in register with the said trouser lacing openings, the upper front portion of the jacket having attaching members at its front upper portion adapted to be engaged 115 by the free ends of the said shoulder straps, and lacings interlaced with the said registering lacing openings, one end of each lacing being secured to the jacket and the other end being provided with a hook and a loop 120 on each of the said flaps adapted to be engaged by the hook of the corresponding lacing.

ALBERT G. TUBBS.
LISLE W. SWEET.
